UNITED STATES PATENT OFFICE.

ANTON VERSTEEG, OF HOUSTON, TEXAS.

ROTARY DRILL.

Application filed October 21, 1922. Serial No. 596,114.

This invention relates to new and useful improvements in a rotary drill.

One object of the invention is to provide a drill adapted for use in drilling wells, particularly deep wells, and wherein the drill bit is rotated through the reciprocating movements of an actuating, or driving member.

Another object of the invention is to provide a drill which may be operated through a cable, by means of the ordinary cable tool drilling rig.

A further feature of the invention resides in the provision of a drilling device of the character described which may be readily pulled from or let down into the bore as a unit, and which is of simple construction and may be cheaply and easily manufactured and which will be very effective in use.

With the above and other objects in view the invention has particular relation to certain novel features of construction, operation and arrangement of parts, an example of which is given in this specification and illustrated in the accompanying drawings, wherein:—

Figure 1 shows a fragmentary vertical sectional view of the drill.

Figure 2 shows a fragmentary side elevation.

Figure 3 shows a transverse sectional view taken on the line 3—3 of Figure 2 and,

Figure 4 shows a transverse sectional view taken on the line 4—4 of Figure 1.

In the drawings, the numeral 1 designates the drill bit which may be of any desired construction and form. This bit is attached to the lower end of the tubing 2 whose lower end is outwardly threaded to receive the collar 3, and whose upper end carries a stuffing box 4. Intermediate the ends of said tubing there is formed an annular integral rib 5, and within the tubing there is screwed an elongated nut 6 having internal coarse threads. Fitted through the stuffing box 4 there is an actuating rod 7 whose lower end is provided with coarse threads which intermesh with the threads of the nut 6. The upper end of this rod is preferably square in cross section and is fitted loosely through a correspondingly shaped hole in the nut 8 which is screwed into the barrel 9, and bolted to the rod 7 on opposite sides of the nut 8 are the collars 10, 10. The barrel 9 is preferably formed of two sections screwed together, as shown in Figure 1, and the

lower end of the lower section has an inwardly turned annular flange 11 which closely surrounds the tubing 2, and interposed between this flange and the collar 3 there is a coil spring 12. The upper section of the barrel 9 is provided with a plurality of radiating blades as 13 which work through corresponding slots in the barrel. For convenience in construction this upper section may be cut into lengthwise segments which are held together at their upper and lower ends by means of the cap screws 14, 14. The inner edges of the blades 13 are fastened to yokes 15. Each yoke has end 79 bearings which work on the inwardly extending bolts 16, 16. These bolts are threaded into the barrel 9, and interposed between the bolt heads and the corresponding yokes are the coil springs 17, 17. The outer corners of the blades are rounded off as at 18. A cable 19 is fastened to the upper end of the actuating rod 7 and extends up to the ground surface and is attached to the walking beam of the drilling rig. The barrel 9 and the actuating rod 7 are elevated by said cable and lowered by gravity alternately. The pitch of the threads of the actuating rod 7 is such that as said rod is elevated and lowered it will impart rotary motion to the nut 6 and the tubing 2, and this motion will be imparted to the bit 1. Said tube and bit are of considerable weight so that as the bit rotates back and forth it will remain on the bottom of the bore and will disintegrate the formation. The blades 13 will hold the barrel against rotation by engaging with the well casing 20, or the other walls of the well bore, but their corners being rounded off they will permit an up and down reciprocating motion of said barrel.

When the barrel is dropped it will strike against the resilient seat 12 thus minimizing the shock and preventing the breakage of parts. When it is desired to withdraw the bit from the bore the cable 19 may be pulled upwardly and the flange 11 engages against the collar 5 so that the entire apparatus may be withdrawn from the bore as a unit.

What I claim is:—

1. A well drilling apparatus including a drill bit, a tubular stem to the lower end of which the bit is attached, a stuffing box carried by said stem, a nut within the stem provided with internal coarse threads, an actuating rod working through said stuffing box and threaded through said nut, a reciproca-

105

110

ble barrel to which the rod is attached and means for reciprocating the barrel in a well bore, and a yieldable cushion interposed between the barrel and stem.

5. 2. A drilling apparatus including a drill bit, a tubular stem to the lower end of which the bit is attached, a nut within the stem provided with internal coarse threads, an actuating rod threaded through said nut, 10 a reciprocable barrel formed of lengthwise sections, end caps securing said sections together, a resilient seat carried by the stem provided to receive the downward stroke of the barrel and yieldingly mounted radiating 15 blades carried by the barrel and passing through the wall thereof adapted to engage with the walls of the well bore.

3. A well drilling apparatus including a drill bit, a tubular stem to the lower end of 20 which the bit is attached, a bearing carried by the stem, an actuating rod working through said bearing, said stem and rod

carrying intermeshing coarse threads, a reciprocable barrel to which the rod is attached, means for reciprocating the barrel in 25 the well bore and means preventing the independent rotation of said rod relative to said barrel.

4. A well drilling apparatus including a drill bit, a tubular stem to the lower end 30 of which the bit is attached, a bearing carried by said stem, an actuating rod working through said bearing within said stem, said rod and stem being provided with coarse intermeshing threads, a reciprocable barrel to 35 which the rod is attached, means for reciprocating the barrel in the well bore, means for preventing the independent rotation of said rod relative to the barrel and means for anchoring the barrel against rotation relative 40 to the walls of said bore.

In testimony whereof I have signed my name to this specification.

ANTON VERSTEEG.
